UNITED STATES PATENT OFFICE.

CHRISTIAN AALBORG, OF WILKINSBURG, PENNSYLVANIA, ASSIGNOR, BY MESNE ASSIGNMENTS, TO WESTINGHOUSE ELECTRIC & MANUFACTURING COMPANY, OF EAST PITTSBURG, PENNSYLVANIA, A CORPORATION OF PENNSYLVANIA.

ELECTRIC HEATING DEVICE.

974,329.

Specification of Letters Patent.

Patented Nov. 1, 1910.

Application filed November 19, 1908. Serial No. 463,489.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Electric Heating Devices, of which the following is a specification.

My invention relates to electric heating apparatus, and it has special reference to such devices as are adapted for heating water and other fluids as they pass through a tube or pipe comprising a part of the device.

The object of my invention is to provide an improved fluid-heating device that shall be simple and durable in construction and in which a maximum amount of the heat generated in the resistance element shall be utilized in raising the temperature of the fluid.

Electrical devices for heating water and other fluids and for generating steam are usually so constructed that the resistance elements are operated at very high temperatures relative to those of the tubes through which the fluid passes.

According to my present invention, I utilize a resistance element comprising a strip or ribbon of steel or other suitable conducting material which is first wrapped with insulating material and is then disposed in the heating device under high pressure, as hereinafter pointed out.

The resistance element is preferably insulated by mica or similar material which is not injured by high temperatures, and is as thin as is consistent with the difference in voltage between the resistance element and the adjacent walls of the fluid-conducting tube.

Figure 1 of the accompanying drawings is an elevation and Fig. 2 is a detail view, partially in cross-section, of an electric heating device constructed in accordance with my invention.

Referring to the drawings, the device here illustrated comprises a tube or pipe 1 which is flattened into a substantially elliptical section and is bent into the form of a zig-zag grid, a plurality of rods or bars 2 and 3 which are located between the turns of the

zigzag grid and are held in position by clamping rods 4 and 5, and resistance elements 6 and 7.

The outer ends of the rods 4 and 5 extend through holes or slots in end frames 8 and 9 which are held in position by clamping nuts 10. The inner ends of the rods 2 and 3 are rounded to fit the bends in the zigzag tube, and their outer ends are provided with holes 10^a to receive the rods 4 and 5. The resistance elements are first wrapped in an envelop 11 of insulating material and are then disposed adjacent to the respective sides of the flattened tube, being held firmly in position by the rods 2 and 3 and the end plates 8 and 9.

The ends of the tube are adapted to receive a pipe connection of any suitable kind so that water or other fluid may be caused to flow continuously through the zigzag grid. After the parts are assembled as above indicated, the resistance element and its insulating envelop are subjected to high pressure by means of the clamping bolts or rods 4 and 5 so that practically all the heat generated in the resistance is absorbed by the water or other fluid traversing the tube. The resistance element is completely protected from mechanical injury and the assembled heater occupies a relatively small amount of space and is efficient in operation. The pressure exerted on the resistance element and its insulating envelop is materially increased by reason of the pressure of the fluid within the flattened tube, the section of which tends to assume a circular form.

The resistance strip or ribbon may be of any suitable type, but I prefer to use one which is similar to that illustrated and described in Patent No. 890,856, granted June 16, 1908, to the Hadaway Electric Heating & Engineering Company, upon an application filed by William S. Hadaway, Jr.

It will, of course, be understood that the heater may be indefinitely extended and may comprise a plurality of zigzag grids with their fluid-conducting tubes connected in series or multiple and with the resistance elements connected in any suitable manner. The terminals of the resistance elements may be arranged to suit the service conditions of the device.

Variations in the form of the flattened tube and of the clamping structure may be made within the scope of my invention.

I claim as my invention:

- 5 1. An electric heating device comprising a flattened fluid-containing tube, relatively flat resistance elements disposed adjacent to the respective outer surfaces of the flattened tube and insulated therefrom, and means for 10 firmly pressing the resistance elements against the surfaces of the tube.
- 15 2. An electric heating device comprising a zigzag grid of flattened fluid-containing tubing and resistance elements forced into engagement with the outer surfaces of the flattened tubing and insulated therefrom.
- 20 3. An electric heating device comprising a zigzag grid of flattened fluid-containing tubing, rods or bars disposed between the turns of the grid, relatively flat resistance elements interposed between the adjacent surfaces of the rods or bars and of the tubing and insulated therefrom, and means for compressing the zigzag grid from end to 25 end.
- 25 4. An electric heating device comprising a

flattened fluid-containing tube, an insulated resistance element in close contact with the flat outer surface of the tube, and means for clamping said parts together, the tendency 30 for the tube to assume a circular section under internal fluid pressure being partially relied upon to press the resistance element against the adjacent surface of the tube.

5. An electric heating device comprising a 35 zigzag grid of flattened fluid-containing tubing, rods or bars disposed between the turns of the grid, relatively flat resistance elements interposed between the adjacent surfaces of the rods or bars and of the 40 tubing and insulated therefrom and a clamping frame composed of end pieces and side bolts for compressing the zigzag grid from end to end.

In testimony whereof, I have hereunto 45 subscribed my name this 16th day of November, 1908.

CHRISTIAN AALBORG.
